UNITED STATES PATENT OFFICE.

JAMES T. BONNEY, OF NEW BEDFORD, MASSACHUSETTS.

TENSION-REGULATING DEVICE FOR LOOM-SHUTTLES.

SPECIFICATION forming part of Letters Patent No. 366,296, dated July 12, 1887.

Application filed January 22, 1887. Serial No. 225,233. (No model.)

To all whom it may concern:

Be it known that I, JAMES T. BONNEY, a citizen of the United States, residing at New Bedford, in the county of Bristol and State of Massachusetts, have invented a new and useful Improvement in Tension-Regulating Devices for Loom-Shuttles, of which the following is a specification.

The object of my invention is to produce a simple, cheap, and easily-operated device by means of which the tension on the thread from the shuttle may be perfectly regulated. I attain this object by the device illustrated in the accompanying drawings, in which—

15 Figure 1 is a side elevation of my tension-regulating device. Fig. 2 is a vertical sectional view of the same. Fig. 3 is a view of the wrench by means of which the tension-regulating device is operated. Fig. 4 is a 20 view in cross-section of the shuttle and tension regulating device on the line $x-x$ of Fig. 5. Fig. 5 is a side view of a portion of a shuttle, showing the educt and the tension-regulating device and spindle in dotted lines. 25 Fig. 6 is a top view of the tension device.

In Fig. 1 i represents my tension-regulating device, consisting of a plug of suitable material having its top flat and its bottom preferably rounded, and perforated vertically 30 through its center, with the upper half of the perforation enlarged, and a perforation made in the center of its side to connect with the vertical opening, as is more fully shown in the sectional view of Fig. 2, and a groove 35 formed in its side reaching nearly its entire circumference, as is fully shown in Fig. 1.

In Fig. 2 c is the perpendicular opening, and a is the opening in the side connecting therewith. n are perforations made in the 40 top of the device in order that it may be operated by the wrench, Fig. 3; and b is the groove in the side. The tension-regulating device is seated in the shuttle, as shown in

Fig. 4, which is a cross-sectional view of the shuttle through the center of the seat of the 45 tension-regulating device. The tension-regulating device is held in its seat by means of the bolt or rivet e , which is riveted on the outside of the shuttle at g . The tension-regulating device is seated in the shuttle in such a 50 manner that the opening a shall coincide with the educt r , in order that the thread from the spindle may be unobstructed in its passage through them.

In Fig. 5 is shown a portion of a shuttle 55 with the spindle and tension-regulating device in dotted lines, and the thread t protruding from the educt r .

The operation of the device is as follows: When it is desired to put a certain tension on 60 the thread, the tension-regulating device is turned in its seat by means of the wrench in such a manner that the thread in passing from the spindle s through the openings c and a and out through the educt r will be made to pass 65 around a greater or less portion of the circumference of the groove b . Thus it will be seen that by means of this simple and cheap tension-regulating device the tension on the 70 thread from a shuttle can be perfectly regulated to any desired extent.

Having thus described my invention, what I claim, and desire to secure by Letters Patent, is—

In a loom-shuttle, the combination, with the 75 shuttle body and spindle, of the adjustable plug i , having a central vertical opening, c d , side opening, a , and groove b , constituting a tension-regulating device, and the bolt e , for securing said device in its seat, substantially 80 as shown and described.

JAMES T. BONNEY.
